LONG LIP CRUCIBLE

George R. Peters, Philadelphia, Pa., assignor to Ross-Tacony Crucible Co., Philadelphia, Pa., a corporation of Pennsylvania

Filed June 10, 1955, Ser. No. 514,544

5 Claims. (Cl. 263—48)

This invention relates to long lip crucibles, i.e. crucibles used to melt metals or metal alloys and having a long pouring lip. Such crucibles are particularly useful in many instances, and there has been an increasing demand for them in recent years.

While the present invention is applicable to long lip crucible formed of any material, it is preferred to construct the long lip crucible of this invention of a refractory composition utilizing residual carbon bonding. Experience has shown that such refractory compositions are superior to other compositions in the manufacture and use of crucibles. Examples of carbon bonding compositions are those given in U.S. Patent No. 2,013,625, issued September 3, 1935, to K. E. Buck. Carbon bonding, which results from carbonization of ingredients such as tar and pitch, is highly resistant to weakening at high temperatures and to thermal shock. Consequently, crucibles made of compositions utilizing a residual carbon bonding stand up very well in use and have long life.

In the construction of any long lip crucible, it is necessary to form the long pouring lip separately from the body or pot of the crucible and then attach the lip to the body in the finished crucible. For many years, cement was employed as the sole means of attachment of the long lip to the body or pot. This practice had serious disadvantages but it was followed of necessity for lack of a better method. Some of the disadvantages of this practice are the following. In some instances, the adhesion between the pot and the lip is not adequate to withstand strains imposed on it by the weight of the metal on the lip during pouring and also strains on the lip occasioned by fastening the same to a furnace lining. Moreover, in use of the crucible, corrosive metals will attack the cement and weaken the joint between the lip and the pot. Furthermore, the proper cementing of the long lip to the pot requires expert skill which is more readily available at the place of manufacture than at the place of use by a customer, but on the other hand attachment of the lip at the place of manufacture introduces problems with respect to shipping of the long lip crucible as a whole and the consequent increase of risk of breakage in transit.

In my copending application Serial No. 344,570, filed March 25, 1953, now abandoned, there is disclosed and claimed a method of constructing carbon bonded long lip crucibles by which the lip is effectively integrated with the body or pot. That method eliminates the cemented joint and overcomes the objections thereof with respect to weakness of the joint but, since it involves integration of the long lip with the pot at the time of manufacture, it necessitates shipment of the crucible as a whole to the user, which makes shipment difficult and increases the risk of breakage in transit.

The principal object of the present invention is to provide a long lip crucible construction which obviates all of the above-mentioned objections.

By this invention, there is provided a construction which is comparable in strength to the integrated struc-

2

ture produced by the method of my above-mentioned copending application, but which is less expensive and enables shipment of the crucible with the long lip detached from the body or pot, the lip being easily attachable by the user.

In accordance with this invention, a long lip crucible is provided which comprises a crucible body or pot, a long pouring lip, and interfitting portions on said body and said lip, one of said portions having an open-faced

- 10 recess with an inwardly declined bottom surface and inwardly divergent side surfaces, and the other of said portions being slidably insertable from the top into said recess and having surfaces complementary to said recess surfaces. Preferably, the side surfaces of said recess are 15 divergent both inwardly and upwardly, and the complementary side surfaces of the insertable portion are formed accordingly. Preferably also, the joint surfaces are coated as hereinafter described.

The invention may be fully understood by reference 20 to the accompanying drawing, wherein

Fig. 1 is a perspective view of a long lip crucible constructed according to the present invention;

Fig. 2 is a plan view of the interfitting portions of the pot and the long lip;

- 25 Fig. 3 is a perspective view of the lip attachment portion of the crucible body or pot, without the lip attached thereto;

Fig. 4 is a perspective view of the detached long lip showing the attachment portion thereof; and

- 30 Fig. 5 is a sectional view taken along line 5—5 of Fig. 1.

In the construction of a long lip crucible according to this invention, the body or pot may be formed by molding

- 35 up the lip-attachment portion of the pot by means of suitable forming and tamping tools. The long lip may be formed in a simple press or mold having the desired shape of the lip, the material being placed therein in soft plastic state. Following the formation of the pot 40 and the long lip with the material in plastic state, each is subjected to the usual treatment to effect curing and finishing. Where the pot and the long lip are formed of a refractory mixture utilizing residual carbon bonding, as preferred, the pot and lip are subjected to the usual heat treatment to effect carbonization of the material, after which they may be subjected to the usual glazing operation.

Referring more particularly to the drawing, the preferred form of the long lip crucible, according to this invention, comprises a body or pot 10 having a lip-attachment portion 11, and a long lip 12 having an attachment end portion 13. As may be clearly seen in Figs. 3 and 5, portion 11 of the pot is a thickened wall portion at the upper part of the pot, and this portion has 55 an outwardly facing recess 14, preferably of substantial width and depth, extending downward from the top thereof. By "substantial" is meant large enough to accommodate the meeting end of the lip, said lip having a trough of a size adequate to handle the charge of the crucible and having side walls at least as thick as the walls of the crucible at points where the crucible wall is not thickened. The recess has an inwardly declined bottom surface 15, and it has side surfaces 16 and 17 which are divergent both inwardly and upwardly. Behind 60 the recess is a residual wall portion 14a continuous with the inner wall of pot 10 but thinner by the depth of the recess 14 than thickened wall portion 11. At the top of the pot and behind recess 14, a recess 18 in residual wall portion 14a is provided which constitutes an exit for molten material during pouring.

The long lip 12 is generally of trough form to convey molten material leaving the pot by way of exit 18.

The attachment portion 13 of the lip is of width and depth to fit tightly in recess 14, and has a bottom surface 19 declined toward the entrance end of the lip, and also has side surfaces 20 and 21 which are divergent both upwardly and toward said end. These surfaces are complementary respectively to the surfaces 15 to 17 of recess 14.

Prior to attachment of the lip to the pot, a refractory coating is preferably applied to the interfitting surfaces. A suitable coating is a mixture of 75% calcined powdered Kyanite and 25% fire clay. This coating acts as a drying agent and also retards exuding of the glaze from the crucible. It also makes possible a tighter fit as it fills in the depressions of the rough and uneven surfaces and provides smooth closely-fitting surfaces.

The lip is attachable to the pot simply by inserting the end portion 13 of the lip downwardly into the recess 14 from the top thereof. The interlocking structure possesses great strength, and makes the crucible as a whole as strong as if the lip actually were integrated with the pot. In fact, tests have shown that the interlocking structure is actually the strongest part of the crucible.

In addition to great strength of the juncture between the long lip and the pot, the construction provided by this invention enables shipment of the crucible with the long lip detached from the pot. As previously indicated, this simplifies shipping and lessens the risk of breakage in transit. The long lip is so easily attachable to the pot that anyone can perform the attaching operation. Thus, the lip is easily attachable to the pot at the place of use.

A further advantage of this construction is that the pot may be inserted in a cold furnace without the lip attached thereto, and then the lip may be attached to the pot.

A further important advantage of this construction is that it affords a tight joint between the pot and the long lip, so that no leakage can take place at the joint.

By way of specific example of the preferred form of this invention, in one physical embodiment the pot has an outside diameter of 27", a height of 35", and a wall thickness of 1 3/4". The thickened wall portion has a thickness of approximately 4" and the outwardly facing recess is approximately 1 1/2" deep. The lip has a length of 14 3/4". The interfitting recess and entrance end of the lip are approximately 6" high, 7" wide at the bottom, and 9" wide at the top.

While a preferred embodiment of the invention has been illustrated and described, the invention is not limited thereto but contemplates such modifications and other embodiments as may occur to those skilled in the art.

I claim:

1. A long lip crucible, comprising a crucible body or pot of refractory material having a thickened wall portion at the upper part thereof, said portion having an outwardly facing recess leaving a residual wall portion, said recess extending downward from the top thereof and inwardly to said residual wall portion, said recess having an essentially planar, inwardly declined bottom surface and having essentially planar, inwardly divergent side surfaces, said planar surfaces meeting in corners at angles of at least 90°, and a long pouring lip of refractory material having an entrance end portion dimensioned to fit tightly in said recess with the end of the lip tightly against the residual wall portion, said end portion having an essentially planar bottom surface declined toward said end and having essentially planar side surfaces which are divergent toward said end, said surfaces of the lip being complementary to said surfaces of said recess for interlocking non-twistable engagement of said end portion of the lip with said wall portion by insertion of said end portion downwardly into said recess from the top thereof.

2. A long lip crucible, comprising a crucible body or

pot of refractory material having a thickened wall portion at the upper part thereof, said portion having an outwardly facing recess leaving a residual wall portion, said recess extending downward from the top thereof and inwardly to said residual wall portion, said recess having an essentially planar, inwardly declined bottom surface and having essentially planar, side surfaces which are divergent both inwardly and upwardly, said planar surfaces meeting in corners at angles of at least 90°, and a long pouring lip of refractory material having an entrance end portion dimensioned to fit tightly in said recess with the end of the lip tightly against the residual wall portion, said end portion having an essentially planar bottom surface declined toward said end and having essentially planar side surfaces which are divergent both upwardly and toward said end, said surfaces of the lip being complementary to said surfaces of said recess for interlocking, non-twistable engagement of said end portion of the lip with said wall portion by insertion of said end portion downwardly into said recess from the top thereof.

3. A long lip crucible, comprising a crucible body or pot of refractory material having a thickened wall portion at the upper part thereof, said portion having an outwardly facing recess of substantial width and depth leaving a residual wall portion, said recess extending downward from the top thereof and inwardly to said residual wall portion, said recess having an essentially planar inwardly declined bottom surface and having essentially planar, inwardly divergent side surfaces, said planar surfaces meeting in corners at angles of at least 90°, and a long pouring lip of refractory material having an entrance end portion dimensioned to fit tightly in said recess with the end of the lip tightly against the residual wall portion, said end portion having an essentially planar bottom surface declined toward said end and having essentially planar side surfaces which are divergent toward said end, said surfaces of the lip being complementary to said surfaces of said recess for interlocking, non-twistable engagement of said end portion of the lip with said wall portion by insertion of said end portion downwardly into said recess from the top thereof.

4. A long lip crucible, comprising a crucible body or pot of refractory material having a thickened wall portion at the upper part thereof, said portion having an outwardly facing recess of substantial width and depth leaving a residual wall portion, said recess extending downward from the top thereof and inwardly to said residual wall portion, said recess having an essentially planar, inwardly declined bottom surface and having essentially planar side surfaces which are divergent both inwardly and upwardly, said planar surfaces meeting in corners at angles of at least 90°, and a long pouring lip of refractory material having an entrance end portion dimensioned to fit tightly in said recess with the end of the lip tightly against the residual wall portion, said end portion having an essentially planar bottom surface declined toward said end and having essentially planar side surfaces which are divergent both upwardly and toward said end, said surfaces of the lip being complementary to said surfaces of said recess for interlocking, non-twistable engagement of said end portion of the lip with said wall portion by insertion of said end portion downwardly into said recess from the top thereof.

5. A long lip crucible, comprising a crucible body or pot of refractory material having a thickened wall portion at the upper part thereof, said portion having an outwardly facing recess leaving a residual wall portion, said recess extending downward from the top thereof and inwardly to said residual wall portion, said recess providing an essentially planar bottom ledge and having essentially planar inwardly divergent side surfaces, said planar surfaces meeting in corners at angles of at least 90° and a long pouring lip of refractory material having an entrance end portion dimensioned to fit tightly

in said recess with the end of the lip tight against the wall, said end portion having an essentially planar bottom surface adapted to rest on the bottom ledge of the recess and having essentially planar side surfaces which are divergent toward said end, said surfaces of the lip being complementary to said surfaces of said recess for interlocking non-twistable engagement of said end portion of the lip with said wall portions by insertion of said end portion downwardly into said recess from the top thereof.
